UNITED STATES PATENT OFFICE.

JAMES B. RYAN, OF NEW YORK, N. Y., ASSIGNOR TO THE NEW YORK WOVEN WIRE MATTRESS COMPANY, OF SAME PLACE.

BED-BOTTOM.

SPECIFICATION forming part of Letters Patent No. 599,739, dated March 1, 1898.

Application filed July 21, 1897. Serial No. 645,397. (No model.)

To all whom it may concern:

Be it known that I, JAMES B. RYAN, a citizen of the United States, residing at New York, in the county of New York and State 5 of New York, have invented certain new and useful Improvements in Bed-Bottoms; and I do declare the following to be a full, clear, and exact description of the invention, such as will enable others skilled in the art to which it app-10 pertains to make and use the same.

My invention relates to that class of bed-bottoms which embody woven-wire mattresses; and it contemplates providing such a bed-bottom with cheap, simple, and efficient 15 means for imparting extra strength to and holding the mattress under tension, so as to prevent undue sagging of the same at the center.

The invention will be fully understood from 20 the following description and claims when taken in conjunction with the annexed drawings, in which—

Figure 1 is a plan view of a bed-bottom embodying my invention with the mattress partly 25 broken away. Fig. 2 is a detail transverse section taken in the plane indicated by the line xx of Fig. 1. Figs. 3 and 4 are detail plan views of modifications, and Fig. 5 is a detail 30 plan view of a modification with the mattress partly broken away.

Referring by letter to the said drawings, and more particularly to Figs. 1 and 2 thereof, A indicates the frame of the bed-bottom, which is preferably of the ordinary rectangular 35 form and construction.

B indicates the mattress of woven-wire fabric, which is also of the ordinary construction and is connected to the end bars a of the frame, and C indicates resilient rods, which 40 are preferably of wire, as shown. These rods C are disposed transverse of the bed-bottom at opposite sides of the middle thereof, and they extend through the meshes of the wire mattress and are thereby secured to the same, as illustrated. To these rods C, I connect the ends of one or more (preferably three) 45 helical springs D, which are disposed longitudinally below the fabric and between the said rods C, and are preferably provided with 50 hooks b to permit of their ready connection to the latter. These springs D are stretched and

placed in engagement with the transverse rods C under tension, and in consequence it will be observed that they will hold the fabric B under tension and increase the strength and 55 rigidity of the same, so as to prevent the undue sagging at the center, which is the common objection to woven-wire mattresses. The said springs D increase the tension of the mattress and strengthen the same not only at the 60 points where they are connected, but also throughout the width of the mattress, for it will be seen that when weight is imposed on the mattress it is not imposed direct on the springs, but on the rods C, which will distribute it and cause it to draw uniformly on or stretch all of the several springs.

I prefer to employ the rods C, because they materially increase the efficiency of the springs D. I do not desire, however, to be 70 understood as confining myself to the same, as the springs may be connected with the mattress through the medium of rings C', (see Fig. 3,) or their hook ends b' may be placed in direct engagement with the wire of the 75 mattress, as illustrated in Fig. 4.

In Fig. 5 of the drawings I have illustrated a modification in which a middle transverse bar E is disposed transversely below the mattress B, free from connection therewith at its 80 ends, and two transverse series of longitudinally-disposed springs D' are employed, said springs being interposed between the middle bar E and rods C and connected at their ends to the same, as shown.

While this construction operates to further distribute the weight of a person lying on the mattress upon the several springs and to strengthen and prevent undue sagging of the mattress, yet the construction shown in Fig. 90 1 is preferred because of its simplicity and cheapness.

It will be appreciated from the foregoing that all of the embodiments of my invention are exceedingly cheap and simple and are 95 adapted to be quickly and easily applied to a mattress. It will also be observed that the mattress may be placed under more or less tension and thereby rendered more or less stiff or rigid by stretching the springs to a 100 greater or less extent prior to connecting their ends with the mattress.

Having thus described my invention, what I claim is—

1. A bed-bottom comprising a frame, a mattress of woven-wire fabric attached to the frame, and one or more horizontal, helical springs arranged below and parallel to the mattress; the said springs having their ends connected to the fabric forming the mattress at intermediate points in the length of the same, and being stretched or under tension, whereby they are supported by the mattress and are adapted to prevent sagging of the same, substantially as specified.
2. A bed-bottom comprising a frame, a mattress of woven-wire fabric attached to the same, and the transverse, resilient rods and a series of horizontal, helical springs carried by the fabric forming the mattress; the said rods being disposed at opposite sides of the middle of the bed-bottom and between said middle and the ends and the springs being stretched or under tension and arranged be-

low and parallel to the mattress and extending in the direction of the length of the bed-bottom between the transverse rods and having their ends connected to said rods, substantially as specified.

3. A bed-bottom comprising a frame, a woven-wire mattress or fabric attached to the frame, transverse resilient rods extending through the mesh of the fabric and disposed at opposite sides of the middle of the bottom, a resilient transverse bar arranged between said rods and below the mattress or fabric, and transverse series of longitudinally-disposed springs arranged below the mattress or fabric and connecting the resilient bar with the resilient rods, substantially as specified.

In testimony whereof I affix my signature in presence of two witnesses.

JAMES B. RYAN.
